ALTERNATING CURRENT TELEVISION

Application filed May 5, 1930. Serial No. 450,025.

This invention relates to the transmission and reception of intelligence over wires or through space, and particularly to the transmission and reception of images as in a television system.

In the transmission of images or pictures it is necessary to illuminate the object in some manner. This may be accomplished by scanning the object with a point of light, the reflection or projection of which will register the relative densities of light and shade of the object on a photoelectric cell. These relative densities of light will be transformed into corresponding electrical variations by means of the photoelectric cell which variations may be transmitted to receiving apparatus. It is well known that if these light variations are reproduced before the eye at the rate of 15 cycles per second or faster, they will appear as a picture of the object scanned by the transmitter.

In my copending application Ser. No. 397,826, filed October 7, 1929, a system for the simultaneous transmission and reception of successive unit portions of a scene has been disclosed. In this application an arc traveling at a high rate of speed between two polarized electrode rails in a magnetic field is employed as the scanning and reception medium. As this arc illuminates unit areas of the scene to be transmitted, reflected light from the scene or object is impressed on a photoelectric cell and transformed into electrical vibrations. In the system disclosed in this copending application, direct current energy is used to energize the fields and direct current potential differences to maintain the traveling arc. In the present invention alternating currents are employed as the sole energy sources.

An object of this invention is to accomplish television with transmitting and receiving apparatus containing no moving parts whatsoever.

Another object of the invention is to transmit and receive images electrically with apparatus supplied from a single alternating current energy source.

50 A further object of the invention is to ob-

tain absolute synchrony of transmission and reception.

A still further object of the invention is to obtain a uniform scanning speed during fluctuations of the energy source.

55 A feature of the present invention is the arrangement of the arc and driving fields in series and/or in parallel and supplied from a single alternating current source of comparatively high frequency so that reversals 60 of the field magnetism is accompanied by a reversal of polarity of the arc electrodes, maintaining, therefore, a continuous arc so far as the eye is aware.

Another feature of the invention is the 65 maintaining of a substantially constant driving force for the arc during variations, or fluctuations of the alternating current voltage supply by means of differential windings in a series parallel relationship with the main 70 field winding and the electrodes of the scanning screen.

The invention will be more fully understood with reference to the accompanying drawings in which:

75 Figure 1 is a diagrammatic drawing of one embodiment of a transmitter of the invention.

Fig. 2 is a diagrammatic drawing of one embodiment of a receiver of the invention. 80

Fig. 3 is a schematic drawing of the synchronizing circuit for the transmitter and receiving apparatus in Figs. 1 and 2; and

85 Figs. 4 and 5 are diagrammatic drawings of the power supply for the circuits in the embodiment of the invention shown in Figs. 1 and 2.

90 Referring to the drawings, and particularly to Fig. 1, transmission apparatus is shown in accordance with the invention. Endless electrode rails 5 and 6 are shown in one particular form for scanning an object which may be placed in front of it. This scanning screen may be of any configuration, the one shown being of the horizontal type. 95 The rail electrodes may be enclosed in a vacuum or a gas filled envelope to obtain better regularity and arc form. Projected light from the arc moving over the rails, passes through a pinhole 7 in the camera 8, 100

successively illuminating unit areas of the object. The electrodes have a foreshortened gap 10 for initiating the arc. In series with the arc when formed is a main field winding 11, which for clearness is shown as a single turn terminating at 12, but which in fact is, preferably, a spherical solenoid made up of a plurality of turns. Continuing from the point 12, a differential winding 13 is shown in series with the arc and main field winding but wound in the reverse direction to that of the main field winding and terminating at point 15. It is to be understood, however, that the main field winding 15 may be in shunt to the energy source and the differential winding in series with the arc or vice versa, regulation being accomplished with the aid of the arc characteristic. The arc electrodes 5 and 6 and the two field windings 11 and 13 are supplied with alternating current energy from a master oscillator 16 through the feeders 17 and 18. The master oscillator 16 in addition to supplying alternating current to energize the field and to maintain the arc, further supplies to the elements just mentioned piloting impulses for initiating the arc and framing the image and intermediate impulses which may have a lower amplitude than the piloting impulses. This function of the master oscillator is explained fully in my copending application mentioned above.

As the arc travels from the foreshortened gap 10 over the system horizontally, as shown by the configuration of the scanning screen electrodes, light projected to the object being scanned through pinhole 7 is reflected upon a photoelectric cell 20 or plurality of cells which may be located around the periphery 35 of the screen. Variations in the light falling on the photoelectric cell due to the varying intensities of light and shade between unit areas of the object, are transformed into electrical variations corresponding thereto and impressed upon an amplifier 21 which increases their amplitude to the desired degree.

These current variations corresponding to the light fluctuations are impressed over conductors 23 on a modulator oscillator 22 in which they modulate a carrier wave for transmitting over an antenna system 24. The amplifier 21 and modulator oscillator 22 may be of any well known type. The antenna system 24 may be replaced by a wire 50 system.

The master oscillator 16 has its frequency maintained constant by the use of a crystal control 26 which may have its temperature regulated to maintain its frequency substantially constant.

The transmitter also comprises a synchronizer 28 which has two inputs, one from the master oscillator through conductors 29, and the other from the electrode rail 5 and probes 65 31 over conductors 30. It will be seen from

the drawings that the shunt paths indicated by the points 31 are the source of impulses to one input side of the synchronizer 28, the purpose thereof to be explained hereinafter. The output of synchronizer 28 is impressed 70 on a control field winding 33 through a transformer 34 for the purpose of maintaining a constant scanning arc speed. In the present system the master oscillator 16 is connected to the modulator oscillator 22 for the purpose of impressing on the latter the synchronizing and intermediate impulses for transmittal to the receiver for the purpose of maintaining perfect synchrony between the scanning arc at the transmitter and the arc at the 75 receiver.

Referring now to Fig. 2, the elements shown in the receiving apparatus corresponding to the elements in the transmitting apparatus (Fig. 1) have been indicated by 80 the same numerals with prime indicators. It is to be understood, of course, that the transmitter and receiver may be adapted to alternate in function by the duplication of apparatus as disclosed in the above mentioned co-pending application but which is eliminated in the present disclosure for the purpose of clearness, as it forms no part of the present invention.

The transmitted picture modulations together with the arc currents and the piloting and intermediate synchronizing impulses are received on an antenna system 40 and by detection at the receiver 41 are reduced to the original frequencies impressed on the modulator oscillatory system 22 from the photoelectric cell 20, amplifier 21 and the master oscillator 16. Certain of these frequencies namely the image components from the photo cell 20 are transmitted from the 95 receiver 41 to an amplifier 42 through filter 44, and the other frequencies to a second amplifier 43 through a filter 46. It is to be understood that filters of the band pass type or of the low frequency or high frequency cut-off type may be used for segregating the picture component frequencies from the arc and piloting frequencies depending upon the auxiliary frequencies employed. The arc currents and the piloting and synchronizing 100 impulses after amplification by amplifier 43 are impressed on the differential winding 13', main winding 11' and electrode rails 5' and 6' over conductors 18' and 17'. Variations of light intensity are provided by the varying 105 intensity of the arc as it travels from the foreshortened gap 10' of the receiver over the electrode rails producing an image of the object scanned by the apparatus in Fig. 1. In the present receiving apparatus, it will be 110 observed that a synchronizer 28', a replica of the synchronizer 28 in Fig. 1, is connected to the probe at the foreshortened gap 10' probes 115 31' over conductors 30' and to the receiver over conductors 29'. A full wave rectifica- 120 125 130

tion system 45 which may be of either the chemical or electron tube type, is shown, the purpose thereof to be explained later.

In Fig. 3 is shown a schematic circuit of the synchronizers 28 and 28' of Figs. 1 and 2. Two tubes 50 and 51 are connected in a push pull bridge circuit with a common plate supply 52. The input of tube 50 is from either of the probes at the foreshortened gaps 10 and 10' and the respective probes 31 and 31', these probes being positioned in the path of the arc but insulated from the rails. Assuming for explanatory purposes that the synchronizer circuit of Fig. 3 is synchronizer 28 (Fig. 1), electrode rail 5 and probes 31 are shown in the input of tube 50. The input of tube 51 is shown connected to the master oscillator 16, which will be replaced by the output of the receiver 41 in the system of Fig. 2. The synchronizing circuit further comprises two rectifiers 54 and 56 which are for the purpose of supplying a direct current bias for the respective tubes. The rectifier 56 is effectively connected in the plate circuit of tube 50 through a transformer 57 and the rectifier 54 is effectively connected in the plate circuit of tube 51 through a transformer 58. The output circuits of tubes 50 and 51 are connected to the input circuits of a balanced tube system 60 through the transformers 61 and 62, respectively. Intermediate the output circuit of tube 51 and one of the input circuits of the system 60 is a transformer 63 for shifting the phase of the output currents from this tube 180 degrees. In the inputs of the tubes 50 and 51 are series resistances 69 and 76 for the purpose of controlling the amplitudes of the incoming impulses. Resistance 69 also offers a high impedance across the arc rails.

The system 60 comprises two vacuum tubes 64 and 65 having a common anode energy supply 66 in series with the primary of an output transformer 67. The transformer 67 feeds an amplifier system which in turn is connected to the auxiliary control winding 33 the winding 68 being the primary of the transformer 34.

In Figs. 4 and 5, a diagrammatic representation is made of power distribution systems for the vacuum tubes of the amplifiers, oscillators, modulators and synchronizer circuits. Ordinary power sources shown at 70 and 71, which may be either single or polyphase, are connected to rectification systems 72 and 73 for source 70, and rectification systems 74 and 75 for source 71. These systems may be coupled by transformers 77 and 78, respectively. Since the result of rectification is not generally a pure direct current, but contains alternating components which may interfere with the transmission of the image current components, filters 80, 81, 82 and 83 are employed to eliminate these deleterious ripples. The elements requiring power may

be tapped off as shown by potentiometers 85, 86 and 87 for the system in Fig. 4, and potentiometers 88, 89, 90, 91, 92 and 93 for the system in Fig. 5. The output leads from the filters may be of different voltages. It may be desirable in these rectification systems to employ floating storage batteries as shown at 95, 96 and 97, for the purpose of steadyng the energy supply to the various loads, since the satisfactory operation of the system depends to a certain extent upon the constancy of the voltage from the supply sources.

The operation of the system referred to in Fig. 1 is as follows: A potential difference is impressed across the rails 5 and 6 over conductors 17 and 18 and windings 11 and 13 of sufficient amplitude to initiate an arc. When the arc forms, current will flow in a certain direction through the main field windings 11 and differential field windings 13 in accordance with the polarity of the electrode rails. As the field winding 11 has a preponderance of turns over that of winding 13, there is a differential flux forming a pole in which the arc at the gap 10 is located. The presence of the arc in the field causes a force to be exerted on the arc which drives it along the electrode rails 5 and 6. Since the source is alternating, however, the arc will be driven only a certain distance under these conditions that is, during one half cycle of the supply frequency. However, at the reversal of polarity of the electrodes during the next half cycle, it is obvious that the field will also reverse in polarity, furnishing a driving force in the same direction during this half cycle causing the arc to traverse the scanning field always in the same direction. Analogously, by changing both the field and armature leads to a motor, no change in direction of rotation is made. The initiating half cycle of the supply frequency may be of greater amplitude than the remainder of the wave, reinitiation of the arc being possible at each half cycle because of the immediate previous ionization which permits the arc to form at a lower amplitude. These alternations are at a sufficiently high frequency that any disappearance of the arc at the nodal points is not perceptible to the eye.

Now if for any reason the supply potential rises, the main field 11 will naturally strengthen due to the increased flow of current therethrough, tending to cause a faster motion to the arc over its scanning rails. Strengthening of the main field, however, is substantially eliminated, because the corresponding increase in field strength of the differential windings 13 neutralizes the increase of flux caused by the main winding. The reverse action occurs when the supply voltage drops. In this manner, therefore, constant cyclic speed for the arc over the scanning rails is obtained by use of the differential action of these field windings.

To further obtain constant arc scanning speed the synchronizer 28 is employed in the same manner as that used in the system of my copending application above referred to.

6 However, a brief description thereof will be made here to account for any change in detail.

Referring to Figs. 1 and 3 simultaneously, a piloting impulse which is actually one half 10 cycle of the supply frequency having a high amplitude, serves to initiate the arc on both the transmitter and receiver screens. These piloting impulses, therefore, accomplish the framing of the image, and provide the timing 15 element required for scanning at the transmitter and for synchronous reception of the image at the receiver. Furthermore, these piloting impulses act to maintain a constant cyclic speed of scanning over the entire 20 screen. They will be received in the input circuit of tube 50 over the conductors 30 from the gap probe and at the same instant in the input circuit of tube 51 over conductors 29 directly from the master oscillator 16. If 25 corresponding impulses arrive at the synchronizer at the same instant, no change will take place in the output circuits thereof, since each tube will block the action of the other by increasing the respective grid bias through 30 the rectifiers 54 and 56. Even should the tubes increase their plate currents simultaneously, no effect would occur in the system 60, because of the equal value and opposite phase 35 of the currents reaching system 60. However, if the arc has been advanced through undesirable influences during its travel over the scanning rails, and reaches the gap a trifle in advance of the succeeding impulse from the master oscillator, it will produce an impulse 40 in the input of tube 50, and there will be no increased bias to prevent the functioning of tube 50 as no counter impulse has arrived at tube 51. Tube 50 will now increase its plate current to produce an increase in 45 negative potential on the grid of the tube 51 through the rectifier 56, causing tube 51 to cease to function during operation of tube 50. The succeeding impulses will be received 50 at the synchronizer inputs at the same instant and will have no effect thereon. It will be understood that the lag or advance is only a portion of a cycle, the correction being made during the half cycle. The impulse from the advanced arc will be of the 55 base frequency and in phase with it, since it is produced by the arc which in turn is produced by the base frequency.

The increase of plate current in tube 50 unbalances system 60, is amplified in tube 64 and 60 impressed on the control winding 33 in such a direction as to decrease the field in accordance with the advance of the arc at the shortened gap. In this case the resulting impulse in winding 33 which may be a portion of the cycle is 180° out of phase with

the main field current so as to weaken the field. This phase shift is obtained through the phase shifting properties of the transmission transformers. When the arc is lagging at the gap 10, and tube 51 receives an impulse from the master oscillator 16 before the gap probe impulse is impressed on tube 50, the impulse created by tube 51 is 180° out of phase with the impulse created by tube 50 but in phase with the main field current and consequently increases the field. This time element is accomplished by proportioning the frequency field strength and length of arc electrodes so as to have an anti-node of the returning arc fall at the gap.

To obtain uniform cyclic propagation of the arc over the screen, the shunts 31 are employed. The master oscillator, as stated above furnishes intermediate impulses insufficient to produce an arc in the gap 10, but so timed as to arrive at the synchronizer 28 over conductors 29 at the same instants that the main arc passes the shunts 31 which produce energy impulses in the input circuit of tube 50. These impulses are also so timed that an anti-node of the base frequency occurs when the arc is passing a probe at the proper time and at its right velocity. These intermediate impulses may be periodic half cycles of the supply frequency having an amplitude intermediate that of the piloting impulse and base current. Now if the main arc, traveling over the rails reaches the shunts 31 at the proper time, these impulses will neutralize those received from the master oscillator and no effect will be made upon the control winding 33 as in the case of the piloting impulses. However, if the arc is lagging or is in advance, then the one or the other of tubes 50 and 51 will be actuated and the auxiliary field winding 33 will be strengthened or weakened in accordance thereto with the resultant speeding up or retardation of the traveling arc. The action in system 60 is exactly the same as in the case of the piloting impulses, the frequency thereof being the same. To obtain the proper phase of the control currents in the winding 33, the frequency, field strength and distance between shunts 31 is such that the arc passes the shunts at an anti-node of the supply frequency. The resistances 69 and 76 may be adjusted to obtain a zero difference between the amplitudes of the opposing waves the difference between the amplitudes of the type of impulses being controlled at the master oscillator. It is to be understood that the piloting and synchronizing or intermediate impulses may be composed of harmonics of the base frequency, the employment of rectifiers then being necessary to produce the proper field directional effects.

In the receiving system of Fig. 2, there is a substantial duplication of the reactions occurring in the apparatus of Fig. 1. The

basic supply frequency with its piloting and synchronizing impulses is received from the antenna 40 together with the frequencies from the photoelectric cell 20. As the arc travels over the rails it has superimposed upon it photoelectric cell currents to produce varying intensities of the arc which appear as the image of the object scanned. The wave shape of the piloting and intermediate impulses may be in the form of a sine wave but preferably of a peaked nature, in order to obtain a more sharp and positive action. By means of filter 46, the basic arc frequency is impressed on amplifier 43 while by means of filter 44 only the photoelectric cell vibrations are impressed on amplifier 42 and rectifier 45. The basic arc frequency propagates the arc, the piloting impulses frame the image and maintain a constant cyclic scanning speed, while the intermediate impulses maintain a uniform propagation of the arc over the image screen in the same manner as in the transmitter of Fig. 1 which has been explained above. However, currents corresponding to the light and shade of the object are superimposed upon this arc to form the image. At certain periods during this superimposition, the photoelectric cell frequencies and the arc frequency will be in phase and out of phase causing alternate fading and strengthening of portions of the images resulting in distortion thereof. This is corrected by the use of rectifier 45 which reverses half cycles of the photoelectric cell waves. Rectification when the currents are not in phase does not interfere with reception so that a rectifier may be placed in the circuit at all times. It is understood, of course, that the amplitudes will not be comparable, but to eliminate any loss of definition in the picture, it is preferable to use the rectifier, although it is not always required. Furthermore, as in the system disclosed in my co-pending application mentioned above, the modulated carrier frequencies of the picture components may be impressed directly on the screen electrodes without demodulation or rectification.

This embodiment of an alternating current transmission and receiving system has been shown with the arc and field in series but it is to be understood that the arc and the field may be placed in a parallel series relationship, the same reaction occurring as in a series relationship. When the polarity of the rails is changed, the polarity of the field is simultaneously changed and the travel of the arc is maintained in the same direction. Furthermore, other synchronizing arrangements may be employed without departing from the spirit of this invention, and although the invention has been disclosed in one particular embodiment, it is understood that it is to be limited only by the scope of the appended claims.

I claim:

1. A television transmission system comprising, an electrodynamic arc screen, a source of energy for said arc, a field for producing a driving force on said arc, means for transforming varying intensities of light into corresponding variations in electrical currents, and common supply means for said arc and said field of an alternating character. 70

2. A television transmission system comprising, an electrodynamic arc screen, a field winding for said screen, a common source of energy of an alternating character for said arc and said field, means for transforming varying intensities of light into corresponding variations in electrical currents, and means for maintaining a substantially constant cyclic speed for said arc during fluctuations in the common energy source. 75 80

3. A television transmission system comprising, an electrodynamic arc screen, a field for said screen, means for transforming varying intensities of light into corresponding variations in electrical currents, and means for supplying said system solely from an 85 alternating current source. 90

4. A television transmission system comprising an electrodynamic arc screen, a field winding supplying a flux for said screen, a common energy source for said arc and said field winding of an alternating character, means for transforming varying intensities of light into corresponding variations in electrical currents, and means for varying the field of said arc for maintaining the cyclic value of said field flux substantially constant. 95 100

5. A television system in accordance with claim 4, in which said means includes an auxiliary field winding in series opposition with said first field winding. 105

6. An illuminating screen comprising a propagated arc in a magnetic field and electric rails for said screen forming adjacent arc paths, said arc and said magnetic field being supplied with alternating currents. 110

7. In a television system, a transmitter scanning screen, means for initiating an electrodynamic arc and an arc driving magnetic field in said screen, a receiver comprising a receiving screen and means controlled by said first means for initiating an electrodynamic arc and a magnetic field in said receiver screen, said arcs and said fields being supplied with alternating current. 115

8. In a television system, a transmitter having a scanning screen, means for producing an electrodynamic arc and an arc driving magnetic field in said screen, a receiver comprising a receiver screen and means for producing an electrodynamic arc in a magnetic field in said receiver screen, and means controlled by said transmitter for synchronizing said arc, said arc and said field being supplied with alternating current. 120 125

9. In a television system, an electrody- 130

- dynamic arc screen including rail electrodes, a magnetic field for operating said arc over said electrodes, an alternating current supply for said field, means for maintaining a substantially constant field during variations of said supply energy, and means for maintaining said arc at a uniform speed.
10. In a system for the transmission of electrical impulses corresponding to light variations defining an object, means for scanning said object with an electrodynamic arc in a magnetic field, a system of electrode rails for determining the path of said arc, and means for operating said arc from an alternating current supply.
11. A system in accordance with claim 10, in which said last-mentioned means includes means for controlling the propagation of said arc in said magnetic field.
20. 12. In a system for the transmission of electrical impulses corresponding to light variations defining an object, means for scanning said object including an electrodynamic arc propagated along electrode rails in a magnetic field, means for operating said scanning system with alternating current, and means for controlling the cyclic speed of said arc and the propagation of said arc in said magnetic field.
30. 13. In a television scanning system, a field coil producing a field flux, a rail electrode system positioned in said field, means for creating an arc between said electrode rails, said arc being propagated over said rails by said field flux, means for directing light from said arc over objects in a two-dimensional pattern, and means for supplying said electrode rails and said field coils with alternating potentials.
40. 14. In a television scanning system, a field coil producing a field flux, electrode rails positioned in said flux, an alternating potential on said electrode rails and said field coils for producing a travelling arc along said rails, means positioned in the arc path at points at which an anti-node of the alternating supply potential occurs, and means for energizing a thermionic device with energy obtained at said points, the output of said thermionic device being utilized to control the speed of said arc.
50. 15. In a television system, a field coil producing a field flux in a certain direction, a second field coil producing flux in the opposite direction, one of said coils producing a predominate flux, a rail electrode system positioned in the resultant field of said coils, means for creating an arc between said electrode rails, said arc being propagated through said field by said resultant flux, means for directing light from said arc over objects whose images are to be transmitted, means for transforming the light and shade densities over said object into corresponding electrical currents, and means for supplying

said electrode rails and said field coils with alternating potentials.

16. In an electrical system, a field coil producing a field flux, a continuous rail electrode system positioned in said field, means for creating an arc between said electrode rails, a plurality of probes located in the path of said arc at equally spaced intervals along said arc path, a thermionic device connected with said probes, a second thermionic device connected to a source of electric impulses, and means interconnecting said thermionic devices for determining the difference between the arrival of said arc at said probes and the impression of said impulses on said second thermionic device to vary the field flux of said system.

17. In a television transmission system, a differential field coil producing a differential flux, a continuous electrode rail system positioned in said field, said coils and said rails being supplied with alternating potentials, means for obtaining the light from said arc in a two dimensional pattern, means for detecting variations in said light and transforming said variations into electrical currents, means for transmitting said variations to a similar electrode rail system, means at said second rail system for generating impulses at definite time intervals, means for creating at said second screen a second plurality of impulses, and means for combining said impulses to change the field flux of said second screen.
